UNITED STATES PATENT OFFICE

LLOYD M. KEIGHLEY, OF DAYTON, OHIO, ASSIGNOR, BY MESNE ASSIGNMENTS, TO
FRIGIDAIRE CORPORATION, A CORPORATION OF DELAWARE

REFRIGERATING APPARATUS

Application filed January 18, 1926. Serial No. 81,902.

This invention relates to refrigerating systems and particularly to a system in which it is desired to maintain some of several cooling compartments at refrigerating temperatures and to maintain other compartments at refrigerating temperature only as required. The present invention is particularly adapted for use in ice cream coolers where ordinarily there is need for only a portion of the available cooling space but where, under other circumstances, additional cooling space is desired.

One of the objects of the present invention is to provide a refrigerating system in which a number of compartments are cooled from a single compressor, the system being so arranged that some of the compartments are continuously cold, while others are adapted to be cooled only as their service is actually needed. This result is obtained automatically, without any attention on the part of the proprietor, upon the insertion of a can of ice cream or other material to be cooled, into the proper compartment.

Further objects and advantages of the present invention will be apparent from the following description, reference being had to the accompanying drawings, wherein a preferred form of the present invention is clearly shown.

In the drawings:

Fig. 1 is a diagrammatic view of a refrigerating system embodying the invention.

Fig. 2 is a sectional view of the pressure responsive valve for controlling the admission of refrigerant to an auxiliary coil.

Fig. 3 is a sectional view of the automatic valve for controlling the release of refrigerant from an auxiliary coil.

Referring to the drawings, for the purpose of illustration, there are shown at 20 and 21, two refrigerating coils surrounding sleeves 22 and 23 respectively, these sleeves being adapted to receive containers 24 and 25 for ice cream or other substances to be cooled. These two coils are connected in series by a conduit 26. Refrigerant medium is supplied to these coils through a conduit 27 and is withdrawn therefrom through a conduit 28. Conduit 27 is connected by

means of a T 29 to the main supply conduit 30, the entrance of refrigerant into the conduit 30 being controlled by the conventional expansion valve 31. The other opening of T 30 is connected to conduit 32 which supplies refrigerant to coil 33 through the valve 36 and conduit 37. Coil 33 surrounds a sleeve 34 which is similar to sleeves 22 and 23, and is likewise adapted to receive a container 35 for ice cream or other substances to be cooled. Refrigerant is conducted from coil 33 by means of conduit 38, valve 39 and exhaust conduit 40.

Outlet conduits 28 and 40 are joined by means of a T 41 to the main outlet or exhaust conduit 42.

Circulation of refrigerant medium through the system is maintained by a compressor 43, driven by a motor 44 through pulleys 45 and 46, and belt 47. Compressor 43 is connected with a condenser 48 which is in turn connected by the conduit 49 to expansion valve 31. This expansion valve is of a conventional type, responsive to the pressure within the refrigerating coils, opening as the pressure in the coils increases, and closing when the pressure decreases.

The starting and stopping of the motor 44 and compressor 43 is governed by the controller 50 which includes contacts 51 and 52 for opening and closing a circuit 53 to motor 44. The controller 50 includes a metal bellows 54 connected by pipe 55 to the conduit 42, and is therefore responsive to the pressure in the low-pressure side of the refrigerating system. Bellows 54 operates a snap switch 56, including the contacts 51 and 52. When the pressure within the low pressure side of the system is above a predetermined degree, the controller will be in the position shown in full lines in the drawings. After the pressure in the low pressure side has been reduced to a predetermined degree, bellows 54 will collapse to operate snap switch 56 and separate the contacts 51 and 52. Any suitable low pressure controller may be used in the present system, one type being shown in the copending application of Jesse G. King and Sylvester Schweller, Serial No. 670,357, filed October 23, 1923.

Referring particularly to Fig. 2, the valve assembly 36 is shown as comprising a valve body 57 having a valve seat 58 adapted to cooperate with the valve proper 59. The valve 59 is provided with a stem 60, the stem 60 being provided at its upper end with a reduced threaded portion 61 adapted to protrude through a central opening in a circular plate 62, the plate resting on shoulder 63 of the valve stem 60 and being firmly attached to the stem by the nut 64. The upper end of valve body 57 is provided with a reduced portion 65 about which is fitted a circular plate 66, similar in design and of the same diameter as plate 62. Plate 66 is adapted to be fixedly held by means of the shoulder 67 on valve body 63 and the turned-over end of reduced portion 65. Fixed to the plates 62 and 66 is the metallic bellows 68. This bellows is adapted by its expansion and contraction to raise and lower plate 62 and stem 60 and consequently to seat and unseat valve 59.

Valve 59 is normally held unseated by the spring 69 which acts against the movable plate 62. The tension of the spring may be regulated by screw 70, threaded in the U-shaped yoke 71, the lower end of the screw bearing against a U-shaped plate 72 which rests upon spring 69. The extremities of yoke 71 are fastened by means of bolts 73 to valve body 57.

Loosely mounted within the bellows 68 is a metallic sleeve 74 surrounding valve stem 60, and prevented from lateral displacement by means of the turned-over end of portion 65. The object of this sleeve is to limit the contraction of the bellows 68 and thereby prevent its fracture.

The valve body 57 is provided with passages 75, 76 and 77, the passage 75 leading to the conduit 32, passage 76 leading to conduit 37, and passage 77, through which the stem 60 loosely passes, leading from conduit 76 to the interior of the bellows 68. It will thus be seen that an increase of pressure, due to the expansion of refrigerant in coil 33, will be transmitted through conduit 37, passage 76 and passage 77 to the interior of bellows 60, thus expanding the bellows against the action of spring 68 and seating the valve 59 to prevent the further entrance of refrigerant medium through conduit 32 and passage 75 to the coil 33.

Valve body 57 is provided at its lower end with a plug 78 adapted to close an opening 79 in the valve body. This opening is made to permit the grinding of the valve seat.

The valve assembly 39 (Fig. 3) comprises a valve body 80 containing a seat 81 for a valve 82. The valve 82 controls the communication between passage 83 leading from conduit 38 and passage 84 leading to conduit 40. Valve 82 has an upwardly projecting stem 85 adapted to pass through a series of packing members 86 and 87, held firmly in place by a

bushing 88 screw-threaded into the upper part of valve body 80. Members 86 are here shown as flexible gaskets resting on a lead gasket 87, but it is understood that any satisfactory type of packing to prevent leakage past the valve stem may be used.

Valve stem 85 is screw-threaded at its upper end to receive the lower end of a rod 89. Rod 89 projects upwardly through a U-shaped yoke 90, the yoke being fastened at its lower ends by screws 91 to valve body 80. Between the yoke 90 and the upper flattened end 92 of valve stem 85, and surrounding rod 89, is interposed a coiled spring 93. This spring acts normally to force the valve 82 downwardly onto its seat.

The upper end of rod 89 is formed with an eye 94 adapted to make a suitable pivotal connection with one extremity of the bent lever 95 (Fig. 1). Lever 95 is pivoted intermediate its ends as at 96 to any suitable fixed support. The other extremity of the lever is bent to a suitable angle, approximately 90°, as is clearly shown in Fig. 1, and is adapted to project over the opening in sleeve 34. Normally the spring 93 tends to rock lever 95 in a clockwise position, maintaining the lever in the dotted line position, and holding valve 82 on its seat.

In the operation of the system, assuming that sleeves 22 and 23 contain cans of ice cream, while sleeve 34 is empty, and that the compressor 43 is operating, valve 39 will operate to close the return conduit 40 from coil 33, and the circulation of refrigerant through the system will be from compressor 43 to condenser 48, expansion valve 31, thence through evaporating coils 20 and 21 and conduits 28 and 42 back to the compressor. If any refrigerant is present in coil 33, its expansion will cause bellows 68 of valve member 36 to expand against the action of spring 69, thereby seating valve 59 in the dotted line position (Fig. 2) and preventing the further entrance of refrigerant to coil 33. Coil 33 is thus isolated from the remainder of the system.

If an ice cream can is now inserted in sleeve 34, the can itself will move lever 95 from the dotted line position to the full line position (Fig. 1) thus unseating valve 82 to the dotted line position (Fig. 3) and releasing the pressure in coil 33 and bellows 68 to the pipes 42 and 40 under the exhausting action of the compressor. Release of pressure in bellows 68 permits spring 69 to unseat valve 59, thereby allowing the entrance of condensed refrigerant to coil 33 where it expands and passes out through exhaust conduit 40 to the compressor. The refrigerating cycle now takes place through all the coils in the system.

It is to be noted that coil 33 has a greater number of turns than either coils 20 or 31. This increased cooling area, permits the sub-

stance in sleeve 34 to rapidly assume the temperature of those substances in sleeves 22 and 23. Likewise coil 21 has a greater number of turns than coil 20, this construction being particularly suited to coils arranged in series in the maintenance of uniform temperatures.

While the form of embodiment of the present invention as herein disclosed, constitutes a preferred form, it is to be understood that other forms might be adopted, all coming within the scope of the claims which follow.

What is claimed is as follows:

- 15 1. A refrigerating system comprising in combination, a cooling unit, means for supplying a volatile liquid refrigerant to, and withdrawing gaseous refrigerant from said cooling unit, said means including an exhaust conduit, means located in said exhaust conduit for rendering said unit operative, said means being actuated by the act of moving an object to be cooled into communication with said cooling unit.
- 20 2. A refrigerating system comprising in combination, a cooling unit, means for supplying refrigerant medium to, and withdrawing same from said cooling unit, said means including an exhaust conduit, means for putting the unit into communication with said exhaust conduit including a valve in the conduit, and means for mechanically operating the valve by the insertion into the unit of an object to be cooled.
- 25 3. A refrigerating system comprising in combination, a cooling unit, means for supplying refrigerant medium to, and withdrawing same from, said cooling unit, said means comprising inlet and exhaust conduits, means operated by the act of inserting into said unit of an object to be cooled and located in said exhaust conduit for rendering said unit operative, and means in said inlet conduit, responsive to the pressure in said cooling unit and adapted to close said inlet conduit when said exhaust conduit is closed.
- 30 4. A refrigerating system comprising in combination, a cooling unit, means for supplying refrigerant medium to, and withdrawing same from, said cooling unit, said means comprising inlet and exhaust conduits, a valve operated by insertion into said unit of an object to be cooled and located in said exhaust conduit for rendering said unit operative, and a valve in said inlet conduit responsive to the pressure in said cooling unit and adapted to close said inlet conduit when said exhaust conduit is closed.
- 35 5. A refrigerating system comprising in combination, a plurality of cooling units, common means for supplying refrigerant medium to, and withdrawing same from, said units, and means operated by the insertion

into one of said units of an object to be cooled for rendering said unit operative.

6. A refrigerating system comprising in combination, a plurality of cooling units, common means for supplying refrigerant medium to, and withdrawing same from, said units, and a valve operated by insertion into one of said units of an object to be cooled for rendering said unit operative.

7. A refrigerating system comprising in combination, a plurality of evaporating coils adapted to cool a plurality of cooling units, common means for supplying refrigerant medium to, and withdrawing same from said coils, said means including a plurality of exhaust conduits, and means operated by insertion into one of said units of an object to be cooled and located in one of said exhaust conduits for rendering one of said coils operative.

8. A refrigerating system comprising in combination, a plurality of evaporating coils adapted to cool a plurality of cooling units, common means for supplying refrigerant medium to, and withdrawing same from said coils, said means including a plurality of exhaust conduits, and a valve operated by insertion into one of said units of an object to be cooled and located in one of said exhaust conduits for rendering one of said coils operative.

9. A refrigerating system comprising in combination, a plurality of cooling units, common means for supplying refrigerant medium to, and withdrawing same from, said units, and means operated by insertion into one of said units of an object to be cooled for rendering said unit operative, said unit having a larger cooling surface than the other units and being adapted rapidly to assume the temperatures of the other units.

10. In a refrigerating system, a plurality of cooling coils connected in parallel and adapted to refrigerate cooling units, means for supplying refrigerant medium to, and withdrawing same from said coils, said means including a primary exhaust conduit and a secondary exhaust conduit associated with each cooling unit, one of said cooling coils being in constant communication with said primary exhaust conduit, means for putting another of said coils in communication with said primary exhaust conduit including a valve located in its secondary exhaust conduit, and means for mechanically operating the valve by the insertion of an object to be cooled into the cooling unit from which refrigerant is withdrawn by said secondary exhaust conduit, said coil having a greater number of turns than the first and being adapted to readily assume the temperature of the other units.

11. Refrigerating apparatus comprising in combination a refrigerating element including a container for articles to be cooled,

means for circulating refrigerant in intimate thermal association with the container, control means normally preventing circulation of refrigerant and means for actuating the control means to permit the circulation of refrigerant, said actuating means being associated with the container in the path of insertion and removal of articles to be cooled.

12. Refrigerating apparatus comprising
10 in combination a refrigerating element including a container for articles to be cooled, a conduit for circulating refrigerant in intimate thermal association with the container, a normally closed valve preventing circulation
15 of refrigerant thru the conduit and means for opening the valve to permit the circulation of refrigerant, said opening means projecting into the container in the path of insertion and removal of articles to
20 be cooled.

In testimony whereof I hereto affix my signature.
